(57) **CLAIM**

The ornamental design for an adjustable ring as shown and described.

DESCRIPTION

FIG. 1 is a front, top, perspective view of an adjustable ring showing my new design.

FIG. 2 is a front, bottom, perspective view thereof.

FIG. 3 is a front view thereof.

FIG. 4 is a rear view thereof.

FIG. 5 is a top view thereof.

FIG. 6 is a bottom view thereof.

FIG. 7 is a left side view thereof.

FIG. 8 is a right side view thereof.

FIG. 9 is a front, top, perspective view of another adjustable ring showing my new design.

FIG. 10 is a front, bottom, perspective view thereof.

FIG. 11 is a front view thereof.

FIG. 12 is a rear view thereof.

FIG. 13 is a top view thereof.

FIG. 14 is a bottom view thereof.

FIG. 15 is a left side view thereof.

FIG. 16 is a right side view thereof.

FIG. 17 is a front, top, perspective view of another adjustable ring showing my new design.

FIG. 18 is a front, bottom, perspective view thereof.

FIG. 19 is a front view thereof.

FIG. 20 is a rear view thereof.

FIG. 21 is a top view thereof.

FIG. 22 is a bottom view thereof.

FIG. 23 is a left side view thereof; and,

FIG. 24 is a right side view thereof.

The dash-dash broken lines depict portions that form no part of the claimed design. The dash-dot-dash broken lines indicate the boundary of the claimed design beyond which no claim is made. No claim is made to portions which are not shown. The surfaces are lined for contour only.

1 Claim, 18 Drawing Sheets
